STRINGED MUSICAL INSTRUMENT

Johan Emil Hillebrandt, 92 Cleveland St., Orange, N.J.

Filed Oct. 18, 1961, Ser. No. 67,142

Term of patent 14 years

(Cl. D56—1)

FIG. 5

FIG. 2

FIG. 6

Fig. 3Fig. 4

FIGURE 1 is a perspective view of a stringed musical instrument, showing my new design;

FIGURE 2 is a top plan view thereof;

FIGURE 3 is an elevation of the side thereof opposite the side shown in FIGURE 1 taken from the plane of the line 3—3 of FIGURE 2;

FIGURE 4 is an end view taken approximately from the plane of the line 4—4 of FIGURE 3;

FIGURE 5 is a bottom plan view taken from the plane of the line 5—5 of FIGURE 3; and

FIGURE 6 is a transverse vertical sectional view on the plane of the line 6—6 of FIGURE 2.

I claim:

The ornamental design for a stringed musical instrument as shown.
